ELEVATING SCAFFOLD

Harry Soskin, Philadelphia, Pa.

Application August 3, 1943, Serial No. 497,245

10 Claims. (Cl. 304—29)

My invention relates to a new and useful elevating scaffold and has for one of its objects to provide a device of this character including a platform to be raised and lowered by the use of air, fluid, electrically or mechanically operated means.

Another object of this invention is to provide an unique lazy tong structure for elevating the platform from a supporting frame or carriage.

Another object of the invention is to provide braces for the lazy tong units to prevent any undue sidewise swaying which might cause the structure to collapse.

Another object of the present invention is to provide specially constructed lazy tong units that they may be disassembled for shipping or transportation purposes and reassembled at the location where the scaffold is to be used.

A further object of the invention is to provide a removable bed for holding work pieces, for example, air or other duct sections to be installed overhead and to provide means for shifting the bed longitudinally any suitable distance for any desirable purpose and also to provide means for increasing the width of the bed.

A still further object of the invention is to provide a walk supported by hangers on the platform and to provide a ladder or ladders slidably connected with the walk.

The structure may be varied in shape, size and dimensions to constitute an elevating platform, life saving and fire fighting apparatus, lookout tower and many other useful appliances in addition to the scaffold which is used by various mechanics in their particular lines of work.

With the above and other objects in view this invention consists of the details of construction and combination of elements hereinafter set forth and specifically designated by the claims.

In order that those skilled in the art to which this invention appertains may understand how to make and use the same I will describe its construction in detail referring by numerals to the accompanying drawings forming a part hereof, in which—

Fig. 1 is a side elevation of an elevating scaffold constructed in accordance with my invention, said scaffold being shown in an elevated condition with the removable bed thereon supporting an air duct and the near side slides broken off and illustrated in section.

Fig. 2 is a horizontal sectional view of Fig. 1 about midway the height thereof and looking downward.

Fig. 3 is a top plan view of Fig. 1 without the air duct.

Fig. 4 is a side elevation of the scaffold retracted or lowered.

Fig. 5 is an end view of Fig. 1 with the elevat-

ing mechanisms removed to plainly show the construction of the framework.

Fig. 6 is an enlarged fragmentary sectional view on the line 6—6 of Fig. 1.

Fig. 7 is a similar view on the line 7—7 of Fig. 1.

Fig. 8 is an enlarged fragmentary sectional view at one end of the base supporting frame or carriage.

Fig. 9 is a side elevation of the lower part of the apparatus illustrating the use of two operating cylinders.

Fig. 10 is a side elevation of the upper part of the apparatus illustrating the platform without the bed and showing how the walk may be arranged level with the platform.

Fig. 11 is a detail sectional elevation of one form of the sides or side rails of a lazy tong unit.

Fig. 12 is an edge view of one of the side rails, partly in section.

Fig. 13 is an enlarged fragmentary sectional elevation of the scaffold platform frame, the walk and supporting bracket, and the ladder with its mounting.

Fig. 14 is a side elevation or edge view, on a reduced scale, of another form of side rail of a lazy tong unit.

Fig. 15 is a detail view of the mechanical lifting mechanism for operation by hand or a separate prime mover.

Fig. 16 is a sectional elevation of the axis of two units of the lazy tong structure.

Fig. 17 is an elevation of one face of two sets of units of a lazy tong to show the braces.

Fig. 18 is a view of Fig. 17 reversed.

Fig. 19 is an enlarged elevation of one unit with the braces.

Fig. 20 is a similar view of the coacting unit.

Fig. 21 is a section on the line 21—21 of Fig. 20.

Fig. 22 is an enlarged cross sectional view through the axis of a lazy tong unit showing another form of side rail construction.

In carrying out my invention as herein embodied 25 represents the base supporting frame or carriage including a body 26 consisting of channel iron sides and ends, uprights 27 fixed to the body, and horizontal channel iron tracks 28 fixed to the upper portions of the uprights and spaced from and above the sides of the body, parallel with said sides. The carriage is preferably mounted on a suitable running gear of a desirable type such as castors 29.

On the base supporting frame or carriage are mounted a number of lazy tongs 30 comprised of a plurality of units 31, Figs. 17 to 20. Lazy tong units are pivoted together in pairs intermediate their ends to resemble the letter X and contiguous pairs are pivoted together at their ends to produce the complete lazy tong structure. Each

unit comprises, fundamentally, the two sides 32, bars 33 between the sides, common to two units, and bolts 34 projected through the sides and screw threaded into the ends of said bars 33.

The lower ends of the sides of one of the lowermost lazy tongs units of each lazy tongs structures is pivoted at a fixed location to the tracks 28, as at 35, Figs. 1, 8 and 9, and the companion lowermost lazy tongs units have angular or goose neck extensions 36. The angular extensions form elbows, at which points rollers 37, Figs. 7 and 8, are journalled on suitable trunnions 38, such as stud bolts, screwed into the bars 33 at these points, and these rollers run in the tracks 28.

In a similar manner the upper ends of the sides of one of the uppermost lazy tongs units of each of the lazy tongs structures is pivoted at a fixed location to the tracks 39, as at 40, Figs. 1 and 10, of the platform 41. Rollers 42 are journalled on suitable trunnions 43 fixed to the upper ends of the sides of the companion uppermost lazy tongs units which rollers run in the tracks 39 of the platform 41.

The platform consists, primarily, of channel iron sides and ends but may be covered with boards 44 or other flooring elements, such as slatted planks, Fig. 10, and these may be flush with the sides and ends or they may extend beyond the outside edges of said sides and ends. Posts 45 are temporarily mounted along the edges of the flooring and guard devices 46, of pipe, rope, chain and the like, are fastened to said posts to keep persons from stepping off of the flooring at the edges thereof. These same posts and guard means are used in slightly different places in other instances and will be again referred to later.

In order that the lazy tongs structures work in unison, flexible means 47, such as cables, have one of their ends attached to the angular extensions 36 of one lazy tongs structure, then pass around guide pulleys 48 and have their opposite ends attached to the angular extensions of another lazy tongs structure.

To extend or protract the lazy tongs structures and thereby raise the platform 41 and objects associated therewith, a cylinder 49 is mounted on the base frame or carriage adjacent one end with a suitable conduit 50 leading thereto behind the piston 51 and the outer end of the latter is connected with the angular extensions 36 of the distant lazy tongs structure, as by a crosspiece 52. When air, gas, water, oil or other liquid is supplied under pressure from any source to the cylinder 49 through the conduit 50 the piston will be forced outward and one of the lazy tongs structures will be protracted directly while the other will be similarly actuated through the medium of the flexible means 47 to elevate the platform in an even horizontal position.

If desirable, a second cylinder 49a, Fig. 9, may be mounted on the base frame or carriage with but reverse to the cylinder 49 and will also be connected with the source of fluid supply by the branch conduit 50a. The piston 51a in the cylinder 49a is connected with the angular extensions 36 of the opposite lazy tongs structure, as through a cross piece the same as the one numbered 52.

In addition to the cylinder and piston operating means, a flexible pull 53, Figs. 1, 2 and 15, has an end fixed to the cross piece 52 and passes around a guide pulley 54 to the drum 55 on which the other end of said pull 53 is wound. The drum is fixed to a shaft 56 on which is also fixed a gear 57 meshing with a pinion 58 on another shaft 59

with square or equivalent shaped ends to receive a hand crank 60 for manual operation or the socket of an electrically actuated "jimmy" or other separate power unit. With the pinion 58 is associated a ratchet wheel 61 having a dog or ratchet 62 coacting therewith to prevent retrograde movement of the parts until desired.

The lazy tongs units 31 are braced or strengthened by angular braces 63, Figs. 17, 18, 19 and 20, arranged in sets in each half of each unit or on opposite sides of an axis bar 33 and some of the braces form an X while others produce a diamond configuration. In order to permit movement of the units, the braces must be able to swing about the bars 33 whether they be the ones in the axis or at the ends of a unit. To accomplish this I mount several sleeves 64 on each bar 33, and each of the sleeves, except the endmost ones at both ends of the lazy tongs structures, has one or more ears 65 to each of which an end of one or more of the braces are attached by fastening devices 66, such as bolts and nuts. Also certain of the braces are attached to ears 67 projecting from the sides 32 of a unit 31 by the same kind of fastening devices 66. By taking a unit such as shown in Fig. 20 and passing it endwise through the center of a unit such as shown in Fig. 19, the two units can be fastened together to complete a member of the lazy tongs structure.

The sides 32 of each unit 31 may be of any desirable configuration, such as flat, round, rectangular, irregular, solid or hollow. One of such forms is illustrated in Figs. 11 and 12 where tubular sections 68 are shown screwed onto threaded bosses 69 projecting from the bearing members 70. The central bearings have two bosses projecting in opposite directions but the end bearings have only one boss each. Bolts 71 pass through two bosses of different or coacting units, or a boss and a track of the base or platform, and a nut is screwed on the threaded terminal. Where two units are pivoted together to form the axis of a lazy tongs member, a bolt 72 is passed through two contiguous bearings and screwed into a nut 73 or equivalent threaded element mounted in an end of the hollow bar 33a.

Another form of units sides construction is depicted in Fig. 14 in which two bars or tubes 74 are bowed in opposite directions and fixed in grooved bearings 75 or blocks to provide each side and through which bearings the bolts pass as previously described.

A further modification of units sides construction is illustrated in Fig. 22 where 76 denotes two channels of a single side, said channels being arranged in opposed relation with the edges of their flanges abutting and welded together along the joint, as at 76. In a manner similar to that shown in Fig. 11, the sides of a unit are pivoted to the hollow bar 33a by bolts 72 which are screwed into the nuts 73 fixed in said bar.

When it is desirable to have a walk disposed below the platform 41, as in Figs. 1 to 6, inclusive, and 13, brackets 77 are hung on the platform tracks 39 with the feet of said brackets extending outward. To the feet are temporarily attached the posts 45 carrying the safety lines or guard devices 46. On these brackets are mounted the slatted planks 78 which form the walk that extends all around the apparatus although any part may be dispensed with when necessary or preferred.

The planks of the walk have angle irons 79 secured to their side edges so that a toe of each angle projects outward and the underneath faces

of these outwardly projecting toes are engaged by the inturned toes of angle cleats 80 fastened to the legs of a step ladder 81 slidable along the top faces of the angles 79.

In order to transport an article or articles to and mount them, without disturbance, upon the platform, I provide a removable bed 82 detachably mounted on top of said platform and extending down over the sides and ends of the latter. The bed sides and ends are formed from angles so as to fit over the platform and while the bed closely hugs the sides of the platform said bed is longer than said platform in order to be movable lengthwise. A screw 83 is threaded through one or each end of the bed so as to impinge an end of the platform and by screwing such screw inward the bed will be moved longitudinally. This is particularly useful when installing devices overhead such as, for example only, air ducts 84, Figs. 1 and 5. A certain number of sections may be assembled on the bed 82 at a place remote from the scaffold, then transported on the bed to the scaffold and placed on the scaffold platform. The scaffold is then elevated and shifted until the duct on the bed is in line with the previously installed part. The workman on the walk can screw the proper screw 83 inward which will slide the bed longitudinally and cause the male end of the duct to enter the female end of the installed part. After fastening the part on the bed in place to its new supports, the scaffold may be lowered.

As it is often desirable to accommodate articles wider than the bed, a number of sheaths 85 are fixed to the top of said bed transversely thereof and slides 86 are telescoped therein so that some extend from one side of the bed and others extend from the opposite side. To the outer ends of the slides extending on either side of the bed is secured a rail 87 preferably in the form of an angle with one of its toes projecting upwardly to function as a stop to prevent an article from slipping off the bed.

While I have described my invention with particular reference to the use of two or more lazy tongs structures it will be apparent that for a small platform to be used in making inspections, changing electric light bulbs in high places and other small jobs, a single lazy tongs structure can be utilized to be actuated by the cylinders and their plungers.

Of course I do not wish to be limited to the exact details of construction herein shown and described as these may be varied within the scope of the appended claims without departing from the spirit of my invention.

Having described my invention what I claim as new and useful is:

1. The combination with an elevating scaffold including a base, a platform and lazy tongs structures between said base and platform for raising the latter, of a bed removably mounted on said platform, said bed being slightly longer than the platform, and a screw threaded through one end of the bed and contacting an end of the platform.

2. The structure of claim 1 wherein sheaths are fixed to the bed crosswise thereof, slides mounted in said sheaths with some extending from each side of the bed, and rails of angle iron secured to the outer end of the slides.

3. An elevating scaffold consisting of a base body, uprights secured to said body, channel tracks secured to said uprights, lazy tongs structures having the lower ends of one of each of the lowermost members fixed to the track, the lower ends of the other lowermost members having angular extensions, guide pulleys, flexible means secured to the extensions and passing around the guide pulleys to transmit power and motion from one lazy tongs structure to the other, rollers on said other lowermost members at the upper ends of the extensions and fitted in the tracks, a cylinder fixed to the base to receive fluid under pressure, a plunger in said cylinder and having its outer end connected to the angular extensions of one of the lazy tongs structures, a platform consisting of a frame including channel tracks to which the upper ends of one of each of the uppermost members of the lazy tongs structures are secured, and rollers on the others of the uppermost members and fitted in the platform tracks.

4. The scaffold of claim 3, in combination with hangers mounted on the platform, slatted planks on said hangers, angle irons on the longitudinal edges of said planks, a ladder mounted on top of a plank, cleats carried by the legs of the ladder and engaging the angle irons to permit sliding of the ladder without accidental displacement, and safety guard means disposed along the outer edges of the planks.

5. In an elevating scaffold, a lazy tongs structure including units each consisting of two sides, bars between said sides, sleeves on said bars, ears on said sleeves and sides, braces angularly arranged and connected to said ears, and fastening means to connect the several parts together.

6. The structure in claim 5 wherein the sides each consists of two opposed channels with the edges of their toes or flanges fixed together.

7. The structure in claim 5 wherein each of the sides consists of bearing members, threaded lugs projecting from said bearing members, and sections of tubing screwed onto said lugs.

8. The structure in claim 5 wherein each of the sides consists of bearing members having grooves in opposite edges, and bars set in said grooves and fixed to the bearing members.

9. An elevating scaffold comprising an oblong base carriage, and including longitudinal channel tracks facing inward, a platform consisting of channel tracks constituting a frame, a pair of lazy tongs structures having portions attached to the base carriage and platform, rollers on other portions of the lazy tongs structures and operating in the tracks, two cylinders mounted on the base carriage, pistons in said cylinders to operate in opposite directions and each connected to a separate lazy tongs structure, and means, to convey fluid under pressure to said cylinders to protract the lazy tongs structures.

10. An elevating scaffold comprising a base, lazy tongs structures operatively mounted on said base, a platform mounted on the lazy tongs structures, a cylinder fixed on the base in a substantially horizontal position and adapted to receive fluid under pressure, and a plunger in said cylinder having its outer end connected to only one lazy tongs structure.

HARRY SOSKIN.
